FOREIGN PATENT DOCUMENTS

NZ 425530-0001 * 12/2018

Primary Examiner — Kimberly Barnes(74) *Attorney, Agent, or Firm* — PROI Intellectual Property US; Klaus Michael Schmid(57) **CLAIM**

The ornamental design for a blower vacuum, as shown and described.

DESCRIPTION

FIG. 1 is a front View of a blower vacuum showing our design;

FIG. 2 is a rear View thereof;

FIG. 3 is a left side View thereof;

FIG. 4 is a right side View thereof;

FIG. 5 is a top View thereof;

FIG. 6 is a bottom View thereof; and,

FIG. 7 is a perspective rear View thereof.

In the drawings, the broken lines represent portions of the blower vacuum that form no part of the claimed design.

1 Claim, 7 Drawing Sheets(56)
